Primary Examiner — Marianne Pandozzi*Assistant Examiner* — Jae Liang(74) *Attorney, Agent, or Firm* — Knobbe Martens Olson & Bear LLP**CLAIM**

The ornamental design for a cup, as shown and described.

DESCRIPTION

FIG. 1 is a front view of a cup showing my new design, the rear and side views being identical;

FIG. 2 is a front and top perspective view thereof in a first position for use;

FIG. 3 is a front and top perspective view thereof in a second position for use;

FIG. 4 is a top view thereof; and,

FIG. 5 is a bottom view thereof.

The broken lines showing in the figure drawings are included for the purpose of illustration and form no part of the claimed design.
